(No Model.)

F. VIRGIEN.
PIPE WRENCH.

No. 426,223.

Patented Apr. 22, 1890.

UNITED STATES PATENT OFFICE.

FRIEDRICH VIRGIEN, OF YONKERS, NEW YORK.

PIPE-WRENCH.

SPECIFICATION forming part of Letters Patent No. 426,223, dated April 22, 1890.

Application filed April 19, 1889. Renewed March 8, 1890. Serial No. 343,177. (No model.)

To all whom it may concern:

Be it known that I, FRIEDRICH VIRGIEN, of Yonkers, in the county of Westchester and State of New York, a citizen of the United States, have invented certain new and useful Improvements in Pipe-Wrenches, of which the following is a specification.

This invention relates to an improved pipe-wrench which can be readily adjusted for any size of pipe, and which can take hold of the pipe with a firm grip and be instantly detached from the same when the wrench is to be removed; and the invention consists of a pipe-wrench which comprises a main shank having a jaw at its end, a straight side and a rack at the opposite side, and a movable jaw, the shank of which is pivoted to a guide-frame that is guided on the main shank, said guide-frame being provided at one side with a spring-actuated handle-piece and at the other side with an interiorly-toothed section that engages the rack of the main shank. The spring that applies the toothed section of the frame into the rack is applied to a transverse pin of the guide-frame and to the inner end of the movable jaw, and provided at its middle portion with a U-shaped bend that rests on a movable T-piece that slides along the straight side of the main shank, as will be fully described hereinafter, and finally pointed out in the claim.

In the accompanying drawings, Figure 1 represents a side elevation, partly in vertical longitudinal section, through the guide-frame of my improved pipe-wrench. Fig. 2 is a horizontal section taken on line $x-x$, Fig. 1. Fig. 3 is a vertical transverse section on line $y-y$, Fig. 1. Fig. 4 is a side elevation of my improved wrench made for use as a pocket-wrench, and Figs. 5 and 6 are details of a pivoted spring-actuated jaw at the end of the main shank.

Similar letters of reference indicate corresponding parts.

In the drawings, A represents the main shank of my improved pipe-wrench, which shank is provided at one end with a handle A' and at the opposite end with a stationary jaw A². The movable jaw B is pivoted to a guide-frame C, which incloses the main shank A and is readily adjustable on the same.

The main shank A is made smooth on one

side and provided with a rack a at the opposite side, and is provided at the middle part near the rack with depressions a', so as to 55 permit the better taking hold of the main shank A by the fingers of the hand.

The guide-frame C is provided at one side with extensions C', which are connected by a transverse pin C², and that serves as a thumb-rest for moving the guide-frame C. The opposite part of the guide-frame C is provided with a toothed section b, which engages the rack a when the guide-frame is not lifted away from the main shank A. The inner 60 angular or curved end of the movable jaw B rests against a transverse pin d of the guide-frame C and is acted upon by a spring D, fastened on the transverse pin of the guide-frame C, or resting against said pin and bearing on the main shank A', as shown in Fig. 4. The middle part of the spring D is provided with a U-shaped bend that rests on a T-shaped movable bearing E, which is carried along with the guide-frame C when the same 70 is moved along the main shank A. The spring D serves to keep the toothed section b of the guide-frame in mesh with the rack a. By pressing on the thumb-rest in the inverse direction of the arrow x', and thereby moving the 80 guide-frame C against the tension of the spring D, the toothed section b is released from the rack a, thus permitting the guide-frame C to be adjusted on the main shank A. The movable jaw B is thus moved nearer to or farther 85 away from the end of the stationary jaw A', according to the size of the pipe to be gripped. As soon as the wrench is adjusted to the pipe the pressure on the thumb-rest of the guide-frame is relaxed, so that the toothed section 90 b interlocks with the rack a of the main shank A.

In place of a stationary jaw at the end of the main shank A, the end of the main shank may be recessed and provided with a pivoted 95 and spring-actuated jaw A³, as shown in Figs. 5 and 6. This construction of the jaw on the main shank facilitates to some extent the removal of the pipe-wrench from the pipe, as the grip of the jaws is released as soon as the 100 wrench is turned in opposite direction to the gripping direction of the same.

The pipe-wrench can be quickly and effectively applied to pipes of different sizes and

can be manufactured at a comparatively low price, it being also adapted to be made on a smaller scale and used as a pocket pipe-wrench, as shown in Fig. 4.

Having thus described my invention, I claim as new and desire to secure by Letters Patent—

The combination of a main shank provided with a jaw at the outer end and having a smooth side and a rack at the opposite side, a guide-frame embracing said main shank and provided with a thumb-rest at one side and a toothed section at the opposite side for engaging the rack of the main shank, a mov-

able gripping-jaw pivoted to said guide-frame, a spring applied to the inner end of the movable jaw and the thumb-rest of the guide-frame and provided with a U-shaped bend, and a movable T-piece that engages said bend and is adapted to slide along the smooth side of the main shank, substantially as set forth.

In testimony that I claim the foregoing as my invention I have signed my name in presence of two subscribing witnesses.

FRIEDRICH VIRGIEN.
